[57] CLAIM

The ornamental design for a tape cassette storage and carrying case, as shown and described.

DESCRIPTION

FIG. 1 is a front perspective view of a tape cassette storage and carrying case embodying my new design; FIG. 2 is a front elevational view thereof, the rear elevational view being identical; FIG. 3 is a left side elevational view thereof, the right side elevational view being identical; FIG. 4 is a front elevational view thereof, in the open state; FIG. 5 is a bottom plan view thereof; FIG. 6 is a top plan view thereof; FIG. 7 is a cross-sectional view taken along line 7—7 of FIG. 6; FIG. 8 is a cross-sectional view taken along line 8—8 of FIG. 6; FIG. 9 is a reduced scale bottom plan of FIG. 2; FIG. 10 is a modified form of the tape cassette storage and carrying case; and FIG. 11 is a perspective view of the modified form of FIG. 10, the opposite side perspective view being a mirror image.
